GREASE EJECTING SYSTEM

Anthony Bizzarri, New York, N. Y.

Application August 13, 1931, Serial No. 556,756
Renewed April 14, 1933

18 Claims. (Cl. 221—47.1)

My present invention relates to grease dispensing devices, and more particularly, to such devices as may be actuated by hydraulic pressure. I have found that when handling heavy greases 5 such as those used for the lubrication of differential mechanisms of motor vehicles, it is necessary to employ considerable pressure to expel the heavy grease from its container and inject the same into the differential casing. However, by means of the 10 present invention, I provide hydraulically actuated means whereby the ejection of the heavy grease is readily accomplished. In the accompanying specification I shall describe, and in the annexed drawings show two illustrative embodiments of the hydraulically actuated grease dispensing devices of the present invention. It is, however, to be clearly understood that I do not wish to be limited to the exact details of the aforesaid illustrative embodiments herein shown 15 and described for purposes of illustration only.

It is the main object of my present invention to provide devices of the general character specified which are simple in construction, easy and economical to fabricate and assemble, and which 20 are admirably adapted to perform their intended functions, to eliminate the difficulties experienced with existing devices for like purposes. Other objects and advantages of the present invention 25 will in part be pointed out in detail hereinafter, and will in part be obvious to those skilled in the art to which the present invention relates.

In the accompanying drawings, Fig. 1 is a diagrammatic view illustrating one of the aforesaid illustrative embodiments of the present invention in an inoperative position.

Fig. 2 is a similar view of the same in a partially operative position.

Fig. 3 is a like view of the same in a completely operative position.

Fig. 4 is a diagrammatic view of another of the aforesaid illustrative embodiments of the present invention in an inoperative position.

Fig. 5 is a similar view of the same in a partially operative position; and

Fig. 6 is a like view of the same in a completely operative position.

Referring now more in detail to the first of the aforesaid illustrative embodiments of the present 50 invention, and with particular reference to Figs. 1, 2 and 3 of the drawings illustrating the same, the numeral 10 generally designates a reservoir for a hydraulic fluid 11. Journalled in one of the walls of the reservoir and extending therein is the 55 shaft 12 of an electric motor (not shown), said

shaft carrying at the end thereof an eccentric cam 13.

Formed in the reservoir 10 are a plurality, here shown as 4, cylinders 14, 15, 16 and 17, the first two of which constitute part of hydraulic fluid 60 pumps and the second two of which constitute part of heavy grease pumps. The cylinders 14 and 15 are respectively provided with inlets 14' and 15' communicating with the reservoir 10 and operable within these cylinders are plungers 14'' and 15'', at all times in contact with the eccentric cam 13. The cylinders are further provided with outlets 18 and 19 in which operate check valves 20 and 21, the outlets communicating by way of a pipe 22 with the lower end of a grease container 70 23, beneath a piston 24 normally retained in the lower end of the container by means of the tension spring 25. The pipe 22 is provided with a by-pass needle valve 26, the purpose of which will later be described more in detail.

The pipe 22 is provided with an adjustable check valve 27 and connects with a pipe 28, the upper end of which communicates with a cylinder 29 which, in turn, is connected by a pipe 30 with another cylinder 31. The latter cylinder 80 communicates by a pipe 32 with the cylinders 16 and 17 of the grease pumps so as to lubricate said pumps, from which pumps the lubricating oil returns to the reservoir by way of the outlets 16' and 17'. The pipe 28 is provided with an adjustable check valve 33 and a by-pass pipe 34 leading back to the reservoir 10.

Operable in the cylinders 16 and 17 are plungers 35 and 36. The cylinders are provided with outlets 37 and 38, the outlets communicating 90 with return pipes 39 and 40, the purpose of which will later be described. At the points of communication between the outlets 37 and 38 and the return pipes 39 and 40, I provide valves 41 and 42, which are carried by pistons 43 and 44, 95 operable in cylinders 45 and 46. The cylinder 45 communicates by way of a pipe 47 with the hydraulic fluid pipe 28 and the cylinder 46 communicates by way of a pipe 48 with the connection 30 between the cylinders 29 and 31.

The outlets 37 and 38 of the grease pumps also communicate by pipes 49 and 50 with a conduit 51 which may, in turn, communicate with a flexible hose (not shown) or any other means for conveying the heavy grease to the place where it 105 is to be used for lubrication. The pipe 50 is provided with a check valve 52.

Operable in the cylinders 29 and 31 are cylindrical valves 53 and 54, the same being respectively controlled by solenoids 55 and 56.

This completes the description of the first of the aforesaid illustrative embodiments of the hydraulic grease dispensing devices of the present invention and while the operation thereof is believed to be clearly apparent from the foregoing description, the same may be briefly summarized as follows:

With all of the parts in the positions shown in Fig. 1 of the drawings, the hydraulic fluid 11 enters the hydraulic pumps by way of the inlets 14' and 15'. The plungers 14" and 15" force the same out of said cylinders and past the check valves 20 and 21 into the pipe 22. Inasmuch as the spring controlling the check valve 27 is weaker than the spring 25 in the grease container 23, the fluid passes the check valve 27 and enters the pipe 28. From here, the fluid passes the valve 53, enters the connection 30, passes the valve 54 and then enters the return pipe 32. From this pipe, the fluid enters the cylinders 16 and 17 of the grease pumps to lubricate the plungers thereof from whence said fluid returns to said reservoir 10 by way of the outlets 16' and 17'. Of course, the eccentric cam 13 is always being rotated. At the same time the grease plungers 35 and 36 are operating in their cylinders but no grease is being pumped out of the conduit 51 for the reason that any grease passing out of the outlet 57 of the grease container 23 and into the cylinders 16 and 17, passes through the outlets 37 and 38, but returns to the cylinders by way of the pipes 39 and 40, past the open valves 41 and 42.

However, if the valve 53 is closed, as shown in Fig. 2 of the drawings, the hydraulic fluid in the pipe 28 will meet a "head" upon reaching the closed valve and will, therefore, be backed through the pipe 47 into the cylinder 45, where it will act upon the piston 43 to close the valve 41. Now the grease that passes through the outlet 37 of the pump cylinder 16 will be forced through the pipe 49 into the conduit 51 and out of the system to wherever it is to be used. Upon releasing the valve 53, the "head" will be relieved and the piston 43 will return to its normal position, thus opening the valve 41 and again causing the grease passing out of the cylinder 16 by way of the outlet 37 to be returned to such cylinder by way of the pipe 39.

If it is desired to obtain double the quantity of grease, the valve 53 is permitted to remain open and the valve 54 is closed. At that time, the hydraulic fluid in the pipe 28 will pass the valve 53 and build a "head" against the valve 54, thus the fluid will be backed into the pipe 47 and cylinder 45 and into the pipe 48 and cylinder 46. Both pistons 43 and 44 will, therefore, be acted upon to close the valves 41 and 42. This will cause the grease passing out of the cylinders 16 and 17 by way of the outlets 37 and 38 to enter the pipes 49 and 50 from where said grease will pass out of the system by way of the conduit 51. Again, releasing the valve 54 will cause the system to resume its normal inoperative position shown in Fig. 1.

In order to force the grease out of the container 23 by way of the outlet 57, whenever the hydraulic fluid in the pipe 28 meets a "head", in addition to its entering either the cylinder 45 or 46, or both, it is backed into the lower end of the grease container 23, beneath the piston 24, and urges the piston 24 upwardly against the action of the spring 25, thus forcing the grease above the piston out of the container.

As soon as the container 23 has been emptied of its grease content, the valve 26 is opened and the hydraulic fluid in the container 23, beneath the piston 24, will return to the reservoir 10, past the valve 26.

This completes the description of the mode of operation of the aforesaid illustrative embodiment of the present invention.

Referring now more in detail to the second of the aforesaid illustrative embodiments of the present invention, and with particular reference to Figs. 4, 5 and 6 of the drawings illustrating the same, the numeral 70 designates a container for grease, said container housing a piston similar in all respects to the piston 24, but not deemed necessary to be here shown, said piston being adapted to be acted upon by a hydraulic fluid in exactly the same manner as disclosed in the first of the aforesaid illustrative embodiments of this invention.

The container 70 is provided with outlets 71 and 72 respectively communicating with grease cylinders 73 and 74. Operable within the cylinders 73 and 74 are plungers 75 and 76, the plungers being maintained in contact at all times with an eccentric 77, driven by a motor not here shown, by expansion springs 75' and 76'. The cylinders 73 and 74 are further provided with outlets 78 and 79 containing check valves 80 and 81, the outlets communicating respectively with a pipe 82 connected at its other end with a chamber 83 and a pipe 84 connected at its other end with the same chamber. The chamber 83 contains a check valve 85 normally closed by an expansion spring 86. The chamber 85 communicates by way of ports 87 and 88 with a cylinder 89 and the pipe 82 communicates by way of a port 90 with the same cylinder. The cylinder 89 communicates by way of ports 91 and 92 with a return pipe 93 communicating at its other end with the reservoir 70 and the cylinder also communicates by way of a port 94 with an outlet for the entire system. Operable within the cylinder 89 is a triple valve 96 having valve portions 97, 98 and 99, the valve being normally maintained in the position shown in Fig. 4 of the drawings by means of an expansion spring 100.

This completes the description of the aforesaid illustrative embodiment of the present invention and the mode of operation thereof may be briefly summarized as follows:

When it is not desired to use the lubricating system 64 in the aforesaid illustrative embodiment of this invention, the parts are as shown in Fig. 4 of the drawings. As there shown, the grease from the tank 70 is pumped by the plungers 75 and 76 through the pipes 82 and 84. The grease in the pipe 82 enters the cylinder 89 by way of the port 90 and leaves said cylinder by way of the port 91 to the return pipe 93, from where it returns to the container 70. The grease in the pipe 84 enters the chamber 83 and leaves said chamber by way of the port 87 into the cylinder 89. From the cylinder 89 the grease passes through the port 92 to the return pipe 93 from where it again enters the reservoir 70. If it is desired to use the amount of lubricant supplied by one of the pumps 76, for example, the valve 96 is operated so that the valve portion 98 closes the communication between the ports 87 and 92 and opens the communication between the ports 88 and 94. With the parts in these positions, the grease from the pump 75 will, as before, be returned to the container 70. But, the grease from the pump 76, after

5 entering the chamber 83, will not be able to pass out of said chamber by way of the port 87 because of the closed valve portion 98. Instead, it will pass through the port 88, past the open valve portion 99, and out of the system by way of the port 94 and outlet 95.

10 If it is desired to use the output of both of the pumps 75 and 76, the valve 96 is operated so as to close the communication between the ports 90 and 91, close the communication between the ports 87 and 92, and open the communication between the ports 88 and 94. With the parts in these positions, the grease in the pipe 82 will not be returned to the pipe 93 through the ports 90 and 91 because of the closed valve portion 97, but, instead, will pass the check valve 85 and enter the chamber 83 from where it will pass out of the same by way of the port 88, past the valve portion 99 and out of the system by way of the port 94 and outlet 95. The grease in the pipe 84 will enter the chamber 83 and pass out of the same by way of the port 88, past the valve portion 99 and out of the system by way of the port 94 and outlet 95.

15 25 This completes the description of the mode of operation of the second of the aforesaid illustrative embodiments of the present invention.

30 From all of the foregoing, it will be noted that the systems disclosed are simple in construction, easy and economical to fabricate and assemble and admirably adapted to perform their intended functions. Other superiorities and advantages of the present invention will be readily apparent to those skilled in the art to which the present invention relates.

35 What I claim as my invention is as follows:

1. In a lubricating system, a container for heavy grease having a grease outlet and a hydraulic fluid inlet, a reservoir for hydraulic fluid 40 communicating with said inlet, means to force the hydraulic fluid from said reservoir to said container to eject the grease therefrom, means to force the ejected grease to the place where it is to be used, and means communicating with said first and second named means to lubricate the latter.

50 2. In a lubricating system, a container for heavy grease having a grease outlet and a hydraulic fluid inlet, a reservoir for hydraulic fluid communicating with said inlet, means to force the hydraulic fluid from said reservoir to said container to eject the grease therefrom, means to force the ejected grease to the place where it is to be used, and means associated with said first named means to cause said second named means to operate.

55 3. In a lubricating system, a container for heavy grease having a grease outlet and a hydraulic fluid inlet, a reservoir for hydraulic fluid communicating with said inlet, means to force the hydraulic fluid from said reservoir to said container to eject the grease therefrom, means to force the ejected grease to the place where it is to be used, means communicating with said first and second named means to lubricate the latter, and means associated with said first named means to cause said second named means to operate.

60 4. In a lubricating system, a container for heavy grease having a grease outlet and a hydraulic fluid inlet, a reservoir for hydraulic fluid communicating with said inlet, a plurality of pumps to force the hydraulic fluid from said reservoir to said container to eject the grease there-

from, and means to force the ejected grease to the place where it is to be used.

5 5. In a lubricating system, a container for heavy grease having a grease outlet and a hydraulic fluid inlet, a reservoir for hydraulic fluid communicating with said inlet, a plurality of pumps to force the hydraulic fluid from said reservoir to said container to eject the grease therefrom, means to force the ejected grease to the place where it is to be used, and means communicating with said pumps and first named means to lubricate the latter.

10 6. In a lubricating system, a container for heavy grease having a grease outlet and a hydraulic fluid inlet, a reservoir for hydraulic fluid communicating with said inlet, a plurality of pumps to force the hydraulic fluid from said reservoir to said container to eject the grease therefrom, means to force the ejected grease to the place where it is to be used, and means associated with said pumps to cause said first named means to operate.

15 7. In a lubricating system, a container for heavy grease having a grease outlet and a hydraulic fluid inlet, a reservoir for hydraulic fluid communicating with said inlet, a plurality of pumps to force the hydraulic fluid from said reservoir to said container to eject the grease therefrom, means to force the ejected grease to the place where it is to be used, means communicating with said pumps and first named means to lubricate the latter, and means associated with said pumps to cause said first named means to operate.

20 8. In a lubricating system, a container for heavy grease having a grease outlet and a hydraulic fluid inlet, a reservoir for hydraulic fluid communicating with said inlet, means to force the hydraulic fluid from said reservoir to said container to eject the grease therefrom, and a plurality of pumps to force the ejected grease to the place where it is to be used.

25 9. In a lubricating system, a container for heavy grease having a grease outlet and a hydraulic fluid inlet, a reservoir for hydraulic fluid communicating with said inlet, means to force the hydraulic fluid from said reservoir to said container to eject the grease therefrom, a plurality of pumps to force the ejected grease to the place where it is to be used, and means communicating with said first named means and said pumps to lubricate the latter.

30 10. In a lubricating system, a container for heavy grease having a grease outlet and a hydraulic fluid inlet, a reservoir for hydraulic fluid communicating with said inlet, means to force the hydraulic fluid from said reservoir to said container to eject the grease therefrom, a plurality of pumps to force the ejected grease to the place where it is to be used, and means associated with said first named means to cause said pumps to operate.

35 11. In a lubricating system, a container for heavy grease having a grease outlet and a hydraulic fluid inlet, a reservoir for hydraulic fluid communicating with said inlet, means to force the hydraulic fluid from said reservoir to said container to eject the grease therefrom, a plurality of pumps to force the ejected grease to the place where it is to be used, means communicating with said first named means and pumps to lubricate the latter, and means associated with said first named means to cause said pumps to operate.

40 12. In a lubricating system, a container for heavy grease having a grease outlet and a hy-
